CLAIM

The ornamental design for a gas composition detection device, as shown and described.

DESCRIPTION

This invention was made with government support under SBIR Phase II Award No. 1632439 awarded by the National Science Foundation. The government has certain rights in the invention.

FIG. 1 is a top, rear, left side perspective view of a gas composition detection device showing the claimed design; FIG. 2 is a bottom, rear, right side perspective view thereof; FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the gas composition detection device that form no part of the claimed design.
